WRITING INSTRUMENT

Noboru Wakai, Tokyo, Japan, assignor to Dai Nihon Bungu Kabushiki Kaisha (also trading as The Japan Stationery Co., Ltd.), Tokyo, Japan, a corporate body of Japan

Filed Jan. 9, 1969, Ser. No. 15,275

Claims priority, application Japan July 13, 1968

Term of patent 14 years

Int. Cl. D19—06

U.S. Cl. D74—17

FIG. 1 is a front perspective view of a writing instrument showing my new design as it appears with the writing point in projected position;

FIG. 2 is a top plan view thereof;

FIG. 3 is a side elevational view thereof as it appears with the writing point in retracted position;

FIG. 4 is a front elevational view thereof;

FIG. 5 is a rear elevational view thereof; and

FIG. 6 is a bottom plan view thereof.

I claim:

The ornamental design for a writing instrument, as shown,
